Filed June 7, 1965, Ser. No. 461,823
1 Claim. (Cl. 46—56)

ABSTRACT OF THE DISCLOSURE

The specification discloses a toy spinning top which is provided with a peripheral turbine means and an air-jet-producing means tangentially aligned with the turbine means so that an air jet produced by either blowing through the air-jet-producing means or by operating a collapsible bulb type of hand pump, or the like, will strike the turbine in a tangential manner and impart rotation to the toy top and cause it to spin in a mounting ring which carries a vertical pivot pin upon which the toy is mounted.

Generally speaking, the present invention relates to the toy top art and, more particularly, to a jet-operated top which, in one preferred exemplary form, is operated by a jet of air either supplied orally or from a collapsible bulb-type of hand pump or the like, although it may be operated by any suitable source of fluid under pressure. The jet-operated top comprises a top body provided with a peripheral, effective turbine means adapted to receive the air or fluid jet and to thereby impart spinning motion to the top which is effectively mounted in a mounting ring which, in a preferred exemplary form, is vertically mounted upon an underlying base so that the device can be suitably mounted, usually upon a substantially horizontal, underlying supporting surface, for subsequent operation by forcibly applying the above-mentioned air or fluid jet to said turbine means.

It will be understood that the top provides a novel toy for children and, in the case of adults, might comprise a humorous device which, in one preferred form, might be labeled with the legend, "Go Ahead and Blow Your Top," and intended for use by a person who is under nervous tension or stress and who gives vent to same or "lets off steam" by operating the top in the manner described above, usually with a humorous aftermath.

With the above points in mind, it is an object of the present invention to provide a novel jet-operated top having the advantages referred to herein and the features referred to herein, generically and/or specifically, and individually or in combination, and which is of extremely simple, inexpensive construction adapted for ready mass manufacture at extremely low cost whereby to be conducive to widespread use thereof.

Further objects are implicit in the detailed description which follows hereinafter (which is to be considered as exemplary of, but not specifically limiting, the present invention), and said objects will be apparent to persons skilled in the art after a careful study of the detailed description which follows hereinafter.

For the purpose of clarifying the nature of the present invention, one exemplary embodiment of the invention is illustrated in the hereinbelow-described figures of the accompanying single drawing sheet and is described in detail hereinafter.

FIG. 1 is an exterior, three-dimensional, pictorial view of one exemplary form of the present invention in fully mounted and operative relationship and, indeed, shows the jet-operated top in the act of being operated by the oral application of a jet of air to the turbine means thereof. The flexible tube used for orally applying the air jet to the turbine means of the top is shown in fragmentary, partially broken away form, as is most of the face and

2

head of the person orally applying air to said tubing. This is done for drawing space saving reasons and since the elimination thereof does not in any way impair the effectiveness of the disclosure of FIG. 1.

FIG. 2 is an enlarged, fragmentary, partially broken away, central plane, sectional view, taken substantially along the plane indicated by the arrows 2—2 of FIG. 1. However, it should be noted that the central spindle means of the top is shown in full elevation rather than in section and that substantially all of the central portion of the hollow top body between the upper end thereof and the lower end thereof is broken away and eliminated for drawing space saving reasons, as is also true with respect to side portions of the underlying, horizontal base means.

FIG. 3 is an enlarged, fragmentary view, substantially entirely in section, although a portion of the tubing means is shown in top plan view, taken substantially along the plane indicated by the arrows 3—3 of FIG. 1 and clearly illustrates the cooperative relationship of the air jet-producing means and the peripheral effective turbine means carried by the hollow top body; said cooperative relationship making it possible to produce or cause rotation of the hollow top body around the vertical, longitudinal spindle means in the manner illustrated in FIG. 1.

Generally speaking, the exemplary form of the invention illustrated may be said to comprise a mounting ring, such as generally designated at 10, which is adapted to be mounted with respect to a supporting base member, such as is generally designated at 12, and which is adapted to engage an auxiliary supporting surface, such as that shown fragmentarily at 14 in FIG. 1, for positioning the mounting ring 10 in a desired spacial orientation with a top body, such as is generally designated at 16, rotatively mounted by a longitudinal spindle means, such as is generally designated at 18, within the mounting ring 10 for relative rotation around the longitudinal axis of said spindle means 18 when a jet-producing means, generally designated at 20, effectively applies a jet of fluid to an effective turbine means such as is generally designated at 22.

The structure of the exemplary form of the invention just described in general form, is clearly illustrated in FIG. 1 in a particular exemplification thereof which will now be described in greater detail with respect to particular aspects of the exemplary form illustrated.

In said particular exemplary form illustrated, it will be noted that the mounting ring 10 may effectively be said to comprise a very short cylinder, such as would be produced by cutting a short length from a large diameter tube—for example, four-inch diameter aluminum tubing having a wall thickness of perhaps $\frac{3}{16}$ inch, for example, although not specifically so limited, may have a very short length cut therefrom to form the ring 10 which, in the preferred exemplary form illustrated, is fastened in an upright, vertical position by the welding 23 which effectively connects same to a horizontal top panel portion 24 of the substantially horizontal base means 12 which is made of a flat, thin-sheet, metal blank having extended corner portions which are then folded down at an angle of substantially 45 degrees (although not specifically so limited) whereby to form the downwardly directed foot portions or feet 26 adapted to rest upon the horizontal underlying surface 14. This provides a very simple and inexpensive structure highly suitable for the purposes of the present invention, although it should not be construed as specifically limiting the invention thereto in all forms thereof.

Also in the exemplary form illustrated, the hollow top body 16 may actually comprise three parts, in addition to the spindle means 18, including the upper top body portion 16U, the lower top body portion 16L, which is

substantially similar to the upper top body portion 16U, although positionally reversed, and the intermediate centrally positioned previously mentioned turbine means 22, which effectively comprises a central peripheral or outer circumferential portion of the complete hollow top body 16.

In one preferred form, the upper and lower top body portion 16U and 16L might be die cut and/or stamped from thin-sheet material, such as thin-sheet aluminum or the like, although not specifically so limited, and the central turbine means might be similarly made. The three portions of the hollow top body 16 comprising the upper portion 16U, the lower portion 16L, and the central turbine means 22, may then be suitably joined together mechanically, such as by press-fitting or the like, or they might be soldered, cemented, or otherwise joined together in any desired manner with the longitudinal spindle means 18, of course, being centrally vertically positioned along a longitudinal, central, vertical axis of rotation which lies substantially on the section 2-2 of FIG. 1 and which may be considered to be designated thereby in FIG. 1. Said longitudinal spindle means passes through top and bottom apertures 28 in the upper and lower top body portion 16U and 16L and may be effectively fastened thereto by solder or the like, or by any other suitable means. In fact, in certain cases, it might comprise an effectively keyed or splined connection by appropriately shaping the spindle means 18 and the aperture-defining portions 28 where they engage each other in the locations most clearly shown in FIG. 2.

It should be noted that the longitudinal spindle means 18 has aligned, oppositely outwardly projecting opposite end portions 18E terminating in corresponding oppositely directed pivot points 18P which are rotatively mounted within and received by correspondingly positioned effective receiving recess means 30 carried by opposite inside surface portions of the mounting ring 10 at the top and bottom thereof as is most clearly shown in FIGS. 1 and 2 in the exemplary form of the invention illustrated. This effectively mounts the complete hollow top body 16 for rotation about a longitudinal, vertical axis lying along the center of the longitudinal spindle means 18 and concentric with respect to the hollow top body 16.

The previously mentioned jet-producing means, generally designated at 20 in the exemplary form illustrated, comprises a tube, conduit, or the like, designated by the reference numeral 32 and which, in the example illustrated, comprises a flexible rubber or plastic tube or the like, which has a remote rear end 32R adapted to be supplied with pressurized air (or other pressurized fluid) whereby to cause the entire structure generally designated at 20 to effectively comprise pressurizing means having a forward ejection or emission end portion 32E effectively substantially horizontally carried by the mounting ring 10, preferably in a slightly tangential direction with respect to the peripheral effective turbine means 22 of the hollow top body 16 as is clearly shown in both FIGS. 1 and 3, whereby the act of blowing into the rear end 32R of the tubing 32 will effectively apply pressurized air thereto and will cause air to be emitted from the ejection or emission end 32E in a slightly tangential horizontal direction for impingement upon said peripheral effective turbine means 22 which will, of course, effectively apply torque thereto and to the complete rotatively mounted hollow top body 16 whereby to produce rotation thereof around the axis of rotation thereof coincident with the longitudinal spindle means 18, as is illustrated in FIG. 1.

It will be noted that the jet producing or pressurizing means 20 is so positioned and mounted by the mounting ring 10 as to effectively lie in a plane substantially perpendicular to the longitudinal spindle means and in a direction having the above-mentioned tangential component with respect to said peripheral effective turbine means 22.

In the exemplary form illustrated, the positioning and

mounting of the jet-producing or pressurizing means 20 is provided by an angular aperture means 34 in a side portion 10S of the mounting ring 10, which may be made initially slightly smaller in interior diameter than the exterior diameter of the forward emission end portion 32E of the rubber or elastomeric tube 32 whereby said emission end 32E can be resiliently forced into the mounted relationship shown in FIGS. 1 and 3 and will be frictionally resiliently received and firmly held in the desired side position and in the desired horizontal tangential relationship with respect to the effective turbine means 22. However, this arrangement may be modified by the provision of a permanently tangentially horizontally positioned nozzle or rigid tubing adapted to receive over the rear or outer end thereof, or otherwise engage, the end of the rubber tubing 32 in lieu of the arrangement just described, or various other functional equivalents thereof or may be employed in lieu of the exemplary arrangement illustrated in the figures.

Also, it should be noted that, instead of directly applying a person's mouth, such as is generally designated at 36 in FIG. 1, to the remote rear end 32R of the tube 32 for effectively pressurizing same, an ordinary drinking straw or the like may be slipped into said end 32R and the person's mouth 36 may be applied to the remote end of the straw, thus providing a sanitary arrangement which does not require that the person's mouth 36 actually touches the tube end 32R and, furthermore, this makes it possible to remove and interchange the straw for each subsequent user of the device.

Also, other pressurizing means may be employed in lieu of the person's mouth, such as shown at 36. For example, a hand pump of the collapsible bulb, one-way valved type, or any other functional equivalent thereof including pressurized sources of various other fluids, may be employed in lieu of the specific arrangement illustrated in FIG. 1.

In the exemplary form illustrated, the peripheral effective turbine means 22, as previously mentioned, may be made of die cut and/or stamped thin-sheet material and may effectively be shaped and formed so as to define and provide a circumferential series of angularly directed, asymmetrical, ratchet-type, bucket-defining toothed vane portions 38 encircling the central part of said hollow top body 16 and with all of said toothed vane portions 38 having similarly tangentially inclined outer faces 38F interconnected by inwardly substantially radially directed, rearwardly facing, shoulder surface portions 38S forming, with the corresponding, tangentially forwardly inclined, outer surface portions 38F, acute angles such as is clearly evident from a careful examination of FIG. 3. However, said turbine means 22 may be modified substantially within the broad scope of the present invention provided that it will produce a tangential force component in response to the impingement thereon of pressurized fluid from the pressurizing means 20.

In certain cases, an adjusting screw may be mounted in either the top or bottom portion of the mounting ring 10 adapted to receive the pivot point portions 18P of the spindle means 18 and may have an end-positioned countersunk recess portion equivalent to the corresponding one of the recessed portions 30 shown in FIG. 2, but threadedly adjustable in order to provide the proper tension of the effectively resilient engagement thereof with respect to the pivot points 18P, if desired.

It should be noted that the upper surface of the panel 24 of the base means 12 may be provided with the visibly discernible legend, "Go Ahead and Blow Your Top," formed or die cut therein (or otherwise discernibly carried thereby), as previously mentioned. However, this is not to be construed as specifically limiting the invention since this does not touch upon the real inventive merits of the present invention.

It should be understood that the figures and the specific description thereof set forth in this application are for the purpose of illustrating the present invention and are

not to be construed as limiting the present invention to the precise and detailed specific structure shown in the figures and specifically described hereinbefore. Rather, the real invention is intended to include substantially equivalent constructions embodying the basic teachings and inventive concept of the present invention.

We claim:

1. A jet-operated top comprising: a mounting ring mounted with respect to a supporting base means which is adapted to engage an auxiliary supporting surface for positioning said mounting ring in a desired spacial orientation; a rotary top body provided with longitudinal concentrically positioned spindle means having aligned oppositely outwardly projecting opposite end portions terminating in corresponding oppositely directed pivot points; said mounting ring being provided with a pair of oppositely positioned effective bearing means inside of opposite surface portions of said mounting ring and rotatively receiving said oppositely directed pivot points of said spindle means whereby to rotatively mount said top body within said mounting ring for rotation about a longitudinal axis of rotation in the plane of said mounting ring and extending thereacross; and exteriorly accessible effective turbine means carried by said top body therearound in a plane transverse with respect to said longitudinal spindle means, said effective turbine means comprising a circumferential series of angularly directed asymmetrical ratchet-type bucket-defining toothed vane portions encircling the center part of said top body and with all of said toothed vane portions having similarly tangentially inclined outer faces interconnected by inwardly substantially radially directed rearwardly facing shoulder surface portions forming acute angles with the corresponding tangentially forwardly inclined outer surface portions; said top body being hollow and comprising a thin-sheet upper shell portion, a similar thin-sheet lower shell portion, and an intermediate interconnecting portion formed and shaped to define said effective turbine means and effectively joined to both said upper and lower shell portions whereby to form said hollow top body; said mounting ring, at a

5 side location between the opposed portions thereof having said bearing means, being provided with jet-producing means directed toward said effective turbine means in a plane transverse with respect to said longitudinal spindle means whereby the production and emission of a fluid jet from said jet-producing means will cause the forcible impingement of jetted fluid upon said effective turbine means and will effectively impart a tangential force thereto whereby to effectively apply torque to said top body around said axis of rotation thereof in a manner producing rotation of said top body around said axis of rotation; said jet-producing means comprising a tube having a remote rear end adapted to be supplied with fluid under pressure, whereby to effectively define and provide pressurizing means having a forward ejection and emission end portion effectively carried by said mounting ring in a transverse direction relative to said longitudinal spindle means and in a tangential direction with respect to said effective turbine means of said top body, the mounting of said forward ejection and emission end portion being provided by angular aperture means provided in a side portion of said mounting ring adapted to frictionally receive and firmly hold said forward ejection and emission end portion of said tube in said transverse tangentially directed relationship with respect to said effective turbine means of said top body, the remote rear end of said tube effectively comprising a mouth-engageable portion for effective pressurizing by a person's mouth.
